(57) **CLAIM**

The ornamental design for a sample cup, as shown and described.

DESCRIPTION

FIG. 1 is a perspective view of an embodiment of a sample cup illustrating our new design;

FIG. 2 is a front view thereof, the back view being a mirror image of FIG. 2;

FIG. 3 is a top plan view thereof;

FIG. 4 is a bottom plan view thereof;

FIG. 5 is a front view of a sample cup of FIG. 1, fitting on a primary tube of a first diameter, the back view being a mirror image of FIG. 5; and,

FIG. 6 is a front view of a sample cup of FIG. 1, fitting on another primary tube of a second diameter, the back view being a mirror image of FIG. 6.

The broken lines shown in the figures are for illustrative purposes only and form no part of the claimed design.
